UNITED STATES PATENT OFFICE.

THOMAS H. RICHARDSON, OF LEXINGTON, NORTH CAROLINA.

CLEANING APPARATUS.

1,343,644.

Specification of Letters Patent. Patented June 15, 1920.

Application filed November 28, 1919. Serial No. 341,193.

To all whom it may concern:

Be it known that I, THOMAS H. RICHARDSON, a citizen of the United States of America, residing at Lexington, in the 5 county of Davidson and State of North Carolina, have invented certain new and useful Improvements in Cleaning Apparatus, of which the following is a specification.

The primary object of the present invention resides in the provision of a novel form 10 of steam producing devices for association with clothes washing or cleaning tanks with the steam in passing to the tanks being superheated for drying the same and for 15 obtaining the highest efficiency therefrom, while a return pipe from the steam supply circuit returns the condensation and waste steam to the boiler for reheating.

This application is a continuation in so 20 far as disclosed in the application filed by Thomas H. Richardson on February 6, 1918, bearing Serial No. 215,628 and embodies improvements in the art thereover.

With the above and other objects in view, 25 the invention consists in the novel form, combination and arrangement of parts herein fully described and shown in the accompanying drawing wherein like reference characters indicate similar parts throughout 30 the view which illustrates in side elevation and partially in section a steam generator and cleaning tanks connected thereto.

Referring more in detail to the accompanying drawing, there is illustrated a stand 35 boiler 1 having a filling pipe 2, a drain valve 3, water gage 4 and a steam gage 5, these parts being of ordinary construction.

Steam generating means associated with the boiler 1 includes a gas tank 6 having a 40 hand pump 7 connected thereto for generating gas while a pipe 8 extends from the tank 6 to the burner 9 beneath the boiler 1 for purposes of heating the water therein. A heating device embodying a dyeing vat, 45 is arranged adjacent the boiler 1 and includes a casing 10 supporting a dyeing vat 11 at its upper end and having the compartment 10' into which a burner 12 is positioned, said burner having a pipe connection 13 with the gas tank 6. A pipe 14 extends from the bottom of the boiler into the casing chamber 10' and is looped as at 15 and directed outwardly and upwardly of the casing as at 16 for entry into the boiler 50 as at 17, at a point above the water line as indicated. The looped portion 15 of the

pipe being above the burner 12 will have the water therein heated to a point for the generation of steam which will gather in the upper end of the boiler 1.

A steam supply pipe 18 is connected to the upper end of the boiler 1 and passes through a casing 19 with the part within the casing coiled as at 20 and valve controlled as at 21 at each side of the casing. 65 A burner 22 is positioned in the casing 19 beneath the coil 20 and has a pipe connection 23 with the gas tank 6 for purposes of superheating the steam contained within the coil 20.

A pair of cleaning tanks 24 and a drying tank 25 of similar construction are arranged upon the support for the boiler and heating case 10 and have the steam supply pipe 18 passing therethrough as indicated in the 70 sectional view of one of the tanks 24, that portion of the supply pipe 18 within the tank 24 being perforated as at 26 to permit the steam to escape therefrom and into the compartment at the bottom of the cleaning 75 and drying tanks between the bottom wall 27 and the false bottom 28, each of which is provided with a drain valve 29. As illustrated, the supply pipe 18 at each cleaning and drying tank is provided with a by- 80 pass 30 having adjacent each end thereof a hand controlled valve 31 while the supply pipe 18 at each side of the cleaning and drying tanks is valve controlled, the entering end of the pipe having a hand controlled valve 32 while a check valve 33 at the opposite side of the tank prevents the 85 return of steam or condensation, the hand and check valves 32 and 33 being positioned inwardly of the connections between the 90 by-passes and the supply pipe. The supply pipe beyond the left hand tank 24 will be termed a return pipe 34 which pipe extends through the heater casing 10 to be coiled as at 35 and directly positioned above the 95 burner 12, the return pipe 34 projecting from the opposite side of the casing 10 and having a check valve 36 therein while the pipe extends upwardly into the boiler as at 37 and terminates at a point above the 100 water line therein.

From the above detailed description of the device, it is believed that the construction and operation will at once be apparent, it being noted that the water within the boiler 1 is 110 heated by the burner 9 while the water in the pipe 14 and coil 15 is heated by the burner

12 and the steam generated therein escapes through the pipe 16 into the upper end of the boiler 1. Under control of the valves 21, the steam escaping from the boiler 1 through the supply pipe 18 is superheated in the casing 19 and is thence delivered through the supply pipe 18 to the cleaning and drying vats 24 and 25 respectively. Should it be desired to direct the flow of steam through all of the cleaning and drying vats, the hand valves 31 in the by-passes 30 may be closed while the check valves 33 therein prevent a retrograde flow of the steam. Any condensation or returning steam 15 entering the pipe 34 will be heated in the coil 35 by the burner 12 and returned to the boiler 1 through the pipe 37 and by way of the check valve 36. Should it be desired to eliminate any of the cleaning or drying vats, 20 the hand valves 31 in the by-passes may be regulated to control the direction of flow of the steam, so that the desired vat or vats may be used to the exclusion of others.

While there is herein shown and described 25 the preferred embodiment of the invention, it is to be understood that minor changes may be made therein without departing from the spirit and scope of the invention, as claimed:

30 What is claimed as new is:—

1. A device of the class described comprising a boiler, a water pipe extending from the bottom of the boiler to a point adjacent the upper end thereof above the water line and having a loop adjacent the lower end of the boiler, a heater for said loop, a steam supply pipe extending from the upper end of said boiler, a superheater for said supply pipe, cleaning devices associated with 35 said supply pipe, a return pipe between the supply pipe and the boiler, check valves in the return pipe to prevent a retrograde flow 40

of the steam and a coil in the return pipe positioned above the heater for the aforesaid pipe loop.

2. A device of the class described comprising a boiler, a water pipe extending from the bottom of the boiler to a point adjacent the upper end thereof above the water line and having a loop adjacent the lower end 50 of the boiler, a heater for said loop, a steam supply pipe extending from the upper end of said boiler, a superheater for said supply pipe, cleaning devices associated with said supply pipe, a return pipe between the supply pipe and the boiler, check valves in the return pipe to prevent a retrograde flow of the steam, a coil in the return pipe positioned above the heater for the aforesaid pipe loop, and a valve controlled by-pass in 55 the steam pipe for each cleaning device.

3. A device of the class described comprising a boiler, a water pipe extending from the bottom of the boiler to a point adjacent the upper end thereof above the water line and having a loop adjacent the lower end of the boiler, a heater for said loop, a steam supply pipe extending from the upper end of said boiler, a superheater for said supply pipe, cleaning devices associated with 65 said supply pipe, a return pipe between the supply pipe and the boiler, check valves in the return pipe to prevent a retrograde flow of the steam, a coil in the return pipe positioned above the heater for the aforesaid 70 pipe loop, a valve controlled by-pass in the steam pipe for each cleaning device, and a hand valve and check valve in the supply pipe at opposite sides of each cleaning device and located within the point of connection with the supply pipe of the by-pass.

In testimony whereof I affix my signature.

THOMAS H. RICHARDSON.
